(57) CLAIM

The ornamental design for a gate/door, as shown and described.

DESCRIPTION

FIG. 1 is a top perspective view of a gate/door according to an embodiment of the present invention; and, FIG. 2 is a front elevation view of the gate/door shown in FIG. 1.

The broken lines shown in FIGS. 1 and 2 depict environmental subject matter only and form no part of the claimed design.

1 Claim, 2 Drawing Sheets

FIG. 1

FIG. 2
